FIG. 2.

FIG. 3.

FIG. 4.

FIG. 5.

FIG. 6.

FIG. 7.

FIG. 8.

FIGURE 1 is a top plan view of an egg case separator sheet showing my new design;

FIG. 2 is an elevational view taken from the bottom of FIG. 1;

FIG. 3 is an elevational view taken from the right of FIG. 1;

FIG. 4 is a vertical sectional view on the line 4-4 of FIG. 1;

FIG. 5 is a top plan view of a modified form of egg case separator sheet of my new design wherein the spaced protuberant pyramidal frustum cushions are shorter in length and greater in number;

FIG. 6 is an elevational view taken from the bottom of FIG. 5;

FIG. 7 is an elevational view taken from the right of FIG. 5; and

FIG. 8 is a vertical sectional view taken on the line 8-8 of FIG. 5.

FIGS. 2, 3, 4, 6, 7 and 8 are on a scale larger than that of FIGS. 1 and 5.

The characteristic feature of the design resides in the combination on a generally rectangular egg case separator of a rectangular peripheral rim, a plurality of parallel ribs extending between two opposed sides of the rim and dividing the separator into substantially identical rectangular areas, and a plurality of spaced protuberant pyramidal frustums arranged centrally in each rectangular area in row formation substantially parallel to the dividing ribs.

This is a continuation of my design applications Serial Nos. D. 59,881 and D. 59,882, both filed March 28, 1960, and now abandoned.

I claim:

The ornamental design for an egg case separator sheet, substantially as shown and described.
